UNITED STATES PATENT OFFICE.

ALBERT E. HOLADAY, OF NAUGATUCK, CONNECTICUT, ASSIGNOR TO THE AMERICAN WRINGER COMPANY, OF WOONSOCKET, RHODE ISLAND, A CORPORATION OF RHODE ISLAND.

PRESSURE-ROLL RELEASE FOR WRINGERS.

1,220,125.

Specification of Letters Patent.

Patented Mar. 20, 1917.

Application filed March 31, 1916. Serial No. 88,009.

To all whom it may concern:

Be it known that I, ALBERT E. HOLADAY, a citizen of the United States, residing at Naugatuck, in the county of New Haven and 5 State of Connecticut, have invented certain new and useful Improvements in Pressure-Roll Releases for Wringer, of which the following is a specification, reference being had therein to the accompanying drawing.

This invention relates to a pressure roll release for wringers; the object being to provide novel means for releasing the pressure on the rolls in case that the operator's hand 15 or any other foreign object, should become accidentally caught between the rolls.

Another and further object of my invention is to provide a clothes wringer in which the top bar thereof carrying the pressure screws, is detachably mounted within 20 the frame of the wringer in such a manner that the operator, by striking the releasing spring can release the top bar so as to reduce the pressure on the pressure bar to allow the rolls to separate.

Another and further object of my invention is to provide a pressure release for clothes wringers which is exceedingly simple and cheap in construction and one which 25 can be readily incorporated in the ordinary construction of clothes wringer, now in use.

Other and further objects and advantages of the invention will be hereinafter set forth and the novel features thereof defined by the 35 appended claims.

In the drawing—

Figure 1, is a side elevation of a clothes wringer partly in section, showing the application of my improved pressure release 40 thereto; and

Fig. 2, is a top plan view partly in section, showing the manner of mounting one of the pressure springs of the clothes wringer.

Like numerals of reference refer to like 45 parts in the several figures of the drawings.

In the drawing, 1 indicates the frame of a clothes wringer formed of slotted side bars 2 connected together at their lower ends by a rod 3 and connecting members 4, and at 50 their upper ends by a detachable top bar 5 which fits within the slotted end portions of the side bars 2.

The upper ends of the side bars are provided with U-shaped members 6 extending 55 across the slot on the outer faces of the bars

for connecting the separated portions of the bars together.

Arranged within the lower ends of the slots of the side bars 2 are bearings, not shown, in which the shaft 7 of a lower pressure roll 8 is mounted, said shaft being adapted to be driven by any suitable means such as a crank or drive pulley, as my invention is capable of being used in connection with a hand or power-operated wringer. 65

Arranged above the lower pressure roll 8 is an upper pressure roll 9 carried by the shaft 10 mounted in bearings 11 arranged in the slots of the bars 2, the shafts 10 and 7 being preferably provided with meshing 70 gears, not shown, which are inclosed by gear casings 12.

The bearings 11 carry spring supports 13 in the nature of plugs which are seated in openings formed in the bearings, having 75 head portions which are reduced to form a shoulder 14 against which the end of coiled pressure springs 15 are adapted to abut so as to prevent the springs from rotating. Extending from each gear case is an arm 16 80 having a hooked upper end 17 which extends between the convolutions of the coil spring 15 in such a manner that when the pressure is released on the springs, the gear casings will be raised by the expansion of 85 the springs so as to allow the upper roll free movement, so as to release the pressure instantaneously in case of a foreign object being drawn between the pressure rolls.

Arranged between the side bars of the 90 frame of the wringer is a pressure bar 18 which is provided with plates 19 at its ends having depending stud portions 20 adapted to fit with the upper ends of the coil springs 15, as clearly shown in Fig. 1. 95

The spring supports 13 are provided with oppositely disposed lugs 13' which fit within grooves formed on the walls of the slotted side pieces 2, as shown in Fig. 2, so as to prevent the supports from rotating. 100

The top bar 5 mounted within the slotted end portions of the side pieces 2 between the U-shaped members 6 is provided with a bowed spring 20 having slots 21 through which screws 22 pass for securing the spring 105 in position upon the top bar, said spring resting upon bearing plates 23 arranged to the inside of the screws 22, as clearly shown in Fig. 1.

The ends of the bowed spring 20 are bi- 110

furcated and the arms formed thereby are bent to form spaced eyes 24 in which a transversely arranged pin 25 is mounted carrying a collar 26 forming a roller so as 5 to allow the ends of the spring to move freely when the same is elongated by exerting a pressure on the bowed portion thereof.

Secured to each side of the slot of the end pieces is a hook member 27, herein shown having a central web portion forming sockets to each side thereof which are adapted to receive the outwardly extending ends of the pins 25 so that when the top bar 10 is in position within the slots of the side pieces, the same will be prevented from moving upwardly thereby so as to hold the top bar under normal conditions, in position within the side pieces to form the frame of the wringer.

20 The top bar is provided with recessed portions adjacent each end in which are mounted boxes 28 having their threaded bores arranged to register with vertical openings formed in the top bar and in which are 25 mounted pressure screws 29 the lower ends of which, are adapted to extend in recesses 19' formed in the plates 19 carried by the pressure bar 18 so that the necessary pressure can be brought to bear on the pressure 30 bar which in turn, through the pressure springs, will exert a pressure on the bearings of the upper roller.

In the construction of clothes wringer thus far described, it will be seen that I have 35 provided a wringer in which the top bar thereof is detachably mounted in such a manner that in order to release the pressure on the pressure rolls, it is only necessary to strike the bowed spring which will 40 elongate the same so as to cause the ends carrying the pins 25 to be moved out of the sockets formed in the hook members which will allow the bar to move vertically so as to relieve the pressure of the pressure 45 screws on the pressure bar which in turn, releases the tension of the pressure springs so as to allow the springs to expand and as these springs expand, the gear casings are raised with them by their connection there- 50 to and the upper pressure roll 9 is free to move vertically so that the pressure on any object which has been drawn between the pressure rolls can be instantaneously released, the pressure screws forming stops for 55 the ends of the bowed spring when the same is subjected to an impact, so that as the bowed spring is elongated, the pins carried by the ends thereof will be carried out of the sockets to insure the releasing of the 60 top bar.

From the foregoing description, it will be seen that I have provided a pressure release for clothes wringers which is so constructed that the same can be used in connection with any of the well-known forms

of clothes wringer now in use, either hand wringers or power wringers, but is especially adapted to be used in connection with power wringers where the pressure rolls are rotated at a high rate of speed, so that the pressure on the rolls can be instantaneously released in case of accident. 70

I claim:

1. A clothes wringer, comprising a frame having slotted side bars, pressure rolls 75 mounted within said frame, pressure springs for said rolls, a pressure bar mounted upon said springs within the slots of said side bars, a top bar carrying pressure screws engaging said pressure bar, and a resilient expansible member having means for detachably securing said top bar in position within said frame. 80

2. In a clothes wringer, the combination with the frame thereof, of pressure rolls 85 mounted in said frame, pressure means for said rolls, a top bar detachably mounted within said frame, hooks carried by the side bars of said frame, and a bowed spring mounted upon said top bar having members coöperating with said hooks for holding said top bar in position within said frame. 90

3. A clothes wringer, comprising a frame having a detachable top bar mounted therein carrying pressure screws, hook members 95 carried by the frame, and a bowed spring carried by the top bar having members engaging said hook members for holding said top bar in position within said frame.

4. A clothes wringer, comprising a frame 100 having slotted side bars, bearings mounted in the slots of said side bars, pressure rolls provided with shafts mounted in said bearings, pressure springs mounted on said bearings, a pressure bar mounted upon said 105 springs, a top bar arranged between the slotted ends of the side bars of said frame, pressure screws carried by said top bar engaging said pressure bar, hooks carried by the side bars, and a bowed spring carried by 110 the top bar having pins at its end coöperating with said hooks for holding said top bar in position within said frame.

5. A clothes wringer, comprising a frame having pressure rolls and pressure means for 115 said rolls, hooks carried by the side bars of said frame, and a bowed spring coöperating with said hooks for holding said pressure means in predetermined position.

6. In a clothes wringer, the combination with a frame, of pressure rolls mounted within said frame, pressure springs for said pressure rolls, gear casings, a connection between said gear casings and pressure springs, a pressure bar mounted upon said 125 springs, a top bar carrying screws mounted upon said pressure bar, and means for detachably securing said top bar in position within said frame.

7. A clothes wringer comprising a frame 130

- having pressure rolls and pressure means for said rolls, a movable mounted top bar carrying pressure screws coöperating with said pressure means, and a resilient expandable member having means at its ends for normally holding said bar in position within said frame. 5
8. A clothes wringer having a movably mounted top bar carrying pressure screws, 10 hooks carried by the frame of the wringer, and a bowed spring carried by said bar having members at its ends coöperating with said hooks for holding said bar in position within said frame. 15
9. A clothes wringer, comprising a frame having slotted side bars, bearings mounted in the slots of said side bars, shafts mounted in said bearings carrying pressure rolls, spring supports carried by said bearings, 20 springs mounted upon said supports, a pressure bar carrying plates provided with plugs extending into said springs, a top bar mounted in the upper ends of said slotted side bars, pressure screws carried by said top bar engaging the plates of the pressure bar, 25 hooks carried by the side bars, a bowed spring slidably mounted upon said top bar, and pins carried by the ends of said bowed spring coöperating with said hooks for holding said top bar in position within the side bars. 30
10. A clothes wringer comprising a frame having pressure rolls and pressure means for said rolls, and a resilient expandable member having means for normally holding said pressure means in predetermined position. 35
11. In a clothes wringer, the combination with the pressure rolls thereof, of pressure means for said rolls, a movably mounted top bar, pressure screws carried by said top bar, hooks carried by the frame of said wringer, a bowed spring slidably mounted upon said top bar, bearing plates for said spring, and 40 pins carried by the ends of said spring co-operating with said hooks for normally holding said bar in position within said frame. 45
12. In a clothes wringer the combination with a frame having pressure rolls mounted therein, pressure means for said rolls, a top bar movably mounted in said frame, pressure screws carried by said top bar, hooks carried by the side bars of said frame, a bowed spring slidably mounted upon said top bar, bearing plates for said spring, said 50 spring having eyes at its ends, and pins mounted in the eyes of said spring engaging said hooks for normally holding said top bar in position within said frame. 55
13. A clothes wringer, having pressure rolls, pressure means for said rolls, a top bar carrying pressure screws coöperating with said 60
- pressure means, a bowed spring slidably mounted upon said top bar, bearing plates for 65 said spring, hooks projecting from the side bars of the frame of the wringer, and pins carried by the free ends of said spring coöperating with said hooks for holding said top bar in position within said frame. 70
14. In a clothes wringer, the combination with pressure rolls thereof, of meshing gears carried by the shafts of said rolls, pressure springs for exerting a pressure upon said rolls, gear casings inclosing said gears, arms 75 carried by said gear casings extending into said springs, and means for exerting a pressure upon said pressure springs. 75
15. A clothes wringer comprising a frame having slotted side bars, pressure rolls 80 mounted within said frame, pressure springs for said rolls, meshing gears carried by the shafts of said pressure rolls, gear casings inclosing said gears, arms carried by said gear casings having hooked upper ends connected 85 to said springs, a pressure bar mounted upon said springs, and means for exerting pressure upon said pressure bar. 85
16. A clothes wringer having pressure rolls and pressure means for said rolls, said pressure means including coil springs, meshing gears carried by said pressure rolls, casings inclosing said gears, and arms carried by said casings having hooked ends extending into the convolution of said springs. 90
17. A clothes wringer having pressure rolls and pressure means for said rolls including coil pressure springs, meshing gears carried by said rolls, means for releasing the pressure on said pressure springs, and gear casings inclosing said gears having a connection with said pressure springs so as to move vertically with said springs when the pressure on said springs is released. 100
18. A clothes wringer having pressure rolls, and means for instantaneously releasing the pressure on said rolls, meshing gears carried by said rolls, gear casings inclosing said gears, and a connection between said gear casings and pressure means for raising said gear casings when the pressure is released on said rolls. 105
19. A clothes wringer, comprising a frame having pressure rolls and pressure means for said rolls, a top bar having means for adjusting said pressure means, hooks carried by the side bars of said frame, and a bowed spring coöperating with said hooks for holding said top bar in predetermined position 110 within said frame. 115
